Primary Examiner—Philip S. Hyder

(57) **CLAIM**

I claim the ornamental design for a tool for removing a sewer pop-up valve cap, as shown and described.

DESCRIPTION

FIG. 1 is a top plan view of the “tool for removing a sewer pop-up valve cap” showing my new design, wherein the bottom plan view is identical thereto; and,

FIG. 2 is a front elevation view thereof, and the rear elevation view being identical thereto.

1 Claim, 1 Drawing Sheet

FIG. 1

FIG. 2
